UNITED STATES PATENT OFFICE.

EDWARD B. WESTON, OF DAYTON, OHIO.

FRUIT-BOX.

No. 895,218.

Specification of Letters Patent.

Patented Aug. 4, 1908.

Application filed February 12, 1908. Serial No. 300,674.

To all whom it may concern:

Be it known that I, EDWARD B. WESTON, a citizen of the United States, residing in Dayton, county of Montgomery, and State of Ohio, have invented certain new and useful Improvements in Fruit-Boxes, of which the following is a full, clear, and exact description, reference being had to the accompanying drawings, forming part of this specification.

My invention relates to the construction of boxes out of veneering, such as have long been used for the reception and transportation of berries, fruit, and the like, and it consists of that certain novel construction and arrangement of parts to be hereinafter particularly pointed out and claimed.

The customary manner of constructing these berry boxes is to steam the wood, so that when the sheets of veneering are cut therefrom to form the blanks, they will be pliable and easily bent into shape. These blanks are cut and scored, so as to form when bent into shape a bottom, sides and ends with side extensions to be folded up along the ends and secured by a wire staple. After the blanks have been folded, and the box constructed, they are then dried, and this drying contracts the wood, and the side edges of the box are very apt to split and crack unevenly, so as to be unsightly, and at the same time the side edges are very apt to crack throughout and become disconnected from the bottom, so that the sides become loose and cannot be held in proper position by the usual single staple that is used at the ends.

It is the purpose of my invention to make use of the contraction of the wood in drying the boxes to form a clean cut severance between the bottom and the sides, and in order that under this condition the sides may be held in proper position, I make use of a pair of staples at each end as will be hereinafter described. The severance of the sides from the bottom will also leave a convenient opening along the bottom for ventilation.

In the drawings, Figure 1 is a plan view of the blank, from which the box is constructed. Fig. 2 is a perspective view of the box before drying. Fig. 3 is a cross section of same, and

Fig. 4 is a cross section of the box after it is dried and ready for use.

A blank of veneering is cut and scored, as shown in Fig. 1, to form the box, in which 1 is the bottom, 2—2 the sides, 3—3 the ends, 4—4 and 5—5 the side extensions, or end flaps, which are to be folded up outside of the ends on the lines 6, 7, 8 and 9, and also between the sides and the side extensions on the lines 10, 11, 12 and 13. The blank is also severed between the ends and the side extensions on the lines 14, 15, 16 and 17.

Before the veneer is cut, the wood is steamed, and softened, so that the blank is pliable like card board, and when the blank has been cut and scored, the sides and ends are folded up, and the side extensions 4—5 folded across the ends 3, and locked in position by the two staples 18—19.

In the construction of these boxes, it is not usual to form a score line at 7 and 9, and consequently when the box has been folded in the drying, the blank is very apt to split at the corners between the bottom and the sides, and these cracks are frequently very uneven.

I take advantage of the fact that in the drying, the veneer will shrink, and form the score lines 7 and 9 very nearly through the blank, so that the box when folded and stapled, and placed in the kiln, the shrinking of the wood will sever the bottom from the sides with a clean even cut, and leave an opening 20—20 along each side for proper ventilation. Under these circumstances the two staples 18 and 19 perform an important service in that they hold the sides securely to the ends, and preserve the rigidity and strength of the box. With a single staple at each end, and with the sides severed from the bottom, it will be evident that the sides would only be hung or pivoted on the ends, and the construction would be too loose and unfit for service.

Having thus described my invention, what I claim as new, and desire to secure by Letters Patent, is:

As an improved article of manufacture, a berry or fruit box, constructed of a blank of veneer integral in the first instance, and cut

and scored to form the bottom, ends and sides, with side extensions to fold outside the ends, and a plurality of staples at each end to secure the side extensions and ends, the lines of fold between the sides and the bottom being primarily cut nearly through the blank and subsequently severed on smooth lines

of severance by the shrinkage of the veneer in drying, substantially as described.

EDWARD B. WESTON.
